UNITED STATES PATENT OFFICE.

CHARLES A. BEGHTOL, OF CANON CITY, COLORADO.

CONTACT-FORMER OR LINE-TAPPER.

964,741.

Specification of Letters Patent. Patented July 19, 1910.

Application filed July 3, 1908. Serial No. 441,868.

To all whom it may concern:

Be it known that I, CHARLES A. BEGHTOL, a citizen of the United States, residing at Canon City, in the county of Fremont and 5 State of Colorado, have invented certain new and useful Improvements in Contact-Formers or Line-Tappers, of which the following is a specification.

This invention relates to electrical fixtures, 10 and more particularly to contact formers or line tappers, and has for an object to provide a device of this character which may be applied to ceiling blocks or cleats, sockets, receptacles, lamps, cut-outs, etc., and which 15 will be so constructed whereby a contact may be made with an insulated wire without peeling the same or seriously mutilating it.

A further object of this invention is to provide a device of the above described character 20 whereby contact may be made with insulated wires without disturbing or severing the same.

A very important object of the invention is to provide such a device which will insure 25 engagement of the conductor by the contact member, allowing a considerable range in the location of the conductor transversely of the contact maker. A serious shortcoming of previous devices of this nature has been 30 that the means for holding the conductor has usually constituted a grooved member, the groove being of a considerably larger size than the conductor casing and allowing 35 some play of the members therein; or if held firmly, the conductor may be disposed off the axis of the contact maker, or may not be located exactly in the center of its insulating envelop, and by the use of the 40 present invention such differences in the matter of location of the conductor will not interfere with the proper function of the contact maker.

Other objects and advantages will be apparent from the following description and 45 it will be understood that changes in the specific structure shown and described may be made within the scope of the claims without departing from the spirit of the invention.

In the drawings forming a portion of this 50 specification, and in which like numerals of reference indicate similar parts in the several views, Figure 1 is a perspective view of a ceiling block showing the application of the present invention thereto, Fig. 2 is a detail 55 transverse sectional view on the line

2—2 of Fig. 1, Fig. 3 is a similar view on the line 3—3 of Fig. 1, Fig. 4 is a perspective view of the screw, Fig. 5 is a perspective view of a modified form of my invention, Fig. 6 is a similar view of a further modified 60 form, Fig. 7 is a similar view of a further modified form.

Referring now more particularly to the drawings, there is shown a ceiling block comprising separable members 5 and 6 re- 65 spectively of insulating material.

The member 6, upon its upper face, and adjacent to each end is provided with a transversely extending semicircular recess 7, and this member is also provided with vertically disposed threaded passages 8 which open at their upper ends in the recesses 7. The member 6 is provided with a socket portion 9 of any suitable construction arranged 70 to receive an incandescent bulb 10. The member 5, upon its under side, and adjacent to each end is provided with a transversely disposed semicircular recess 11 arranged to lie in registering opposition to the recesses 7 formed in the member 6, and these recesses 80 thus receive line wires 12 of insulated construction. The member 6 is also provided with a centrally located threaded passage 13 arranged to receive a clamping screw 14 or 85 similar fastening device carried by the member 5 whereby the members 5 and 6 may be firmly held together.

Each threaded passage 8 receives a contact former or line tapper 15 comprising a threaded shank 16 having a head 17 at 90 one end, as shown. A transversely disposed inverted V shaped knife blade 18 projects into the recess 7 formed at each end of the member 6.

It will be seen by reference to Fig. 2 95 that the blade portion 18 extends transversely of the recesses in the adjacent faces of the sections 5 and 6, extending almost the full width thereof, their cutting edges being slightly spaced from the plane of the meeting faces of the sections. It will thus be apparent that whether the line wires 12 are disposed centrally of the recesses or not, they will be in position to be engaged by the blade. Also, as the blade does not project 100 into the recess of the opposite member, there is no liability of the conducting member being entirely severed. After the members 5 and 6 are properly assembled the screw 14 105 may be engaged in the passage 13 whereby 110

the two members are effectively clamped together. Upon operation of the screw 14 to clamp the members 5 and 6 it is obvious that the knife blade of each screw at the 5 ends of the member 6 will puncture or slit the insulation of its respective wire to form contact therewith. Each screw or threaded shank is provided with a transversely disposed passage 19 adjacent to its lower end 10 for the reception of the wires connecting the lamp 10 to the socket 9.

In the modified form of my invention shown in Fig. 5 a screw 20 of ordinary construction is provided including a head 21 therefor having the usual transversely disposed slot 22 formed therein, and in this form of my invention it will thus be seen that screws of ordinary construction may be employed, and as shown in Fig. 5, a 20 knife blade 23 is inserted in the groove and may be secured thereto by welding it to the head or the like.

In the form of my invention shown in Fig. 6 a screw 24 is provided including a 25 head 25 therefor which is provided with a transversely disposed dove tailed groove 26 for the reception of the dove tailed end 27 of a knife blade 28.

In the form of my invention shown in Fig. 7, a screw 29 is provided which carries 30 a washer 30 and a nut 31, and upon reference to this figure it will be seen that a wire may be conveniently clamped between the washer and nut.

35 It will thus be seen that a simple, cheap and effective device is provided which may be constructed on the lines described, and which may be used in connection with electrical fixtures of various description, and 40 effectively serves as a contact former which may be used without greatly mutilating the wire or without disturbing the same as will be readily understood.

What is claimed is:

45 1. As an article of manufacture, a contact former or line tapper comprising an attaching shank, a head carried thereby and an insulation cutting blade carried by the

head and extending laterally at right angles to the major axis of the device. 50

2. As an article of manufacture, a contact former or line tapper comprising a headed shank and a transversely extending blade carried by the head and reaching its periphery on opposite sides for the purposes indicated. 55

3. As an article of manufacture, a contact former or line tapper comprising a threaded shank including a head therefor, and an inverted V-shaped insulation cutting 60 blade carried by the head, said blade projecting longitudinally therefrom and extending transversely of the major axis of the device for the purposes described.

4. As an article of manufacture, a contact former or line tapper comprising a threaded shank having a wire receiving passage extending transversely therethrough, and an insulation cutting knife carried by the shank. 70

5. An electrical fixture of the class described comprising in combination a base member having parallel transversely extending grooves therein and a central opening therethrough, of a superior member having similar transverse grooves in opposed registry with the first named grooves, recesses formed centrally of the last named grooves and passages opening therefrom; and headed shank members engaged in the 80 passages, the heads thereof being disposed within the recesses, and insulation cutting blades carried by the heads projecting longitudinally outward thereof and extending transversely of the grooves, and means for 85 clamping the two members together for the compression of electrical conductors in the grooves and against the blades for the purpose described.

In testimony whereof I affix my signature, in presence of two witnesses.

CHARLES A. BEGHTOL.
